UNITED STATES PATENT OFFICE.

HARRY FEDER, OF NEW YORK, N. Y.

DESIGN FOR SKIRT-BINDING.

SPECIFICATION forming part of Design No. 30,041, dated January 17, 1899.

Application filed December 22, 1898. Serial No. 700,064. Term of patent 14 years.

To all whom it may concern:

Be it known that I, HARRY FEDER, a citizen of the United States, and a resident of New York, in the county and State of New York, have invented and produced a new and original Design for a Skirt-Binding, of which the following is a specification, reference being had to the accompanying drawings, forming a part thereof.

The essential features of my design consist in a skirt-binding comprising a head portion and a brush along the edge of the head portion, the head portion presenting when observed from one side a series of short columns in proximity to the brush portion and differentiated from a series of columns above them and when viewed in end elevation presenting a head portion and a flaring brush portion thickened on one side of the lower edge of the head portion.

In the accompanying drawings, Figure 1 is a view of the skirt-binding in side elevation. Fig. 2 is a similar view looking at the skirt-binding from the opposite side, and Fig. 3 is a view in end elevation.

A represents the head portion; B, the brush; C, the line of columns in proximity to the brush and differentiated from the line of columns *a* above them.

What I claim is—

The design for a skirt-binding substantially as herein shown and described.

In testimony that I claim the foregoing as my invention I have signed my name, in presence of two witnesses, this 28th day of November, 1898.

HARRY FEDER.
